Application November 12, 1931
Serial No. 574,502

15 Claims. (Cl. 242—75)

This invention relates to certain improvements in web roll controlling mechanism, that is, tension devices for controlling the unwinding of rolls of web material, and has been particularly designed for use in controlling the unwinding of web rolls in printing machines.

In feeding the web to the printing mechanism, it is desirable that the web be found under such tension as to produce good printing, such tension being called herein the normal running tension of the web. It is also desirable that additional tension be applied to the web if a slack should occur, due to a break in the web or a sudden stoppage of the press to which the web is being fed. In a copending application of Harry V. Ball and Albert J. Horton, Serial No. 565,940, there is described an improved mechanism which functions to produce a suitable normal running tension on the web and which will act to provide an additional or auxiliary tension, in case of a slack in the web, to quickly stop the web roll and prevent overrunning of the web.

Generally speaking, the construction shown in said application comprises friction belts or straps engaging the surface of the unwinding roll with means for exerting a normal running tension on these straps, a drop roll engaging the running web, and mechanism actuated by the downward movement of the drop roll for causing an increased pull on the straps so as to exert an increased tension on the roll, said construction also including friction bands acting to permit an overtravel of the drop roll so as to take up any slack that might be formed in the web in case the web roll is not instantly stopped by the application of the additional pressure on the straps.

The mechanism shown in this copending application operates entirely successfully for the purpose for which it has been designed, but such mechanism has certain complications which it is desirable to avoid, and it is the especial object of the present invention to provide an improved mechanism of simpler form than that referred to in such application which will function to produce the desired normal running tension on the web and which will provide the additional or auxiliary tension when required, and in which means are provided for permitting an overtravel of the controlling drop roll so as to take up any slack which may be formed in the web in the event that the unwinding web roll is not quickly stopped by the tension devices or straps used for this purpose.

With this and other objects not specifically referred to in view, the invention consists in cer-

tain novel parts, arrangements and combinations which will be fully described in connection with the accompanying drawings and the novel features pointed out in the claims hereunto annexed.

In these drawings, which show a preferred embodiment of the invention,

Figure 1 is an end elevation, partly broken away and partly in section, embodying the improvements of the present invention;

Figure 2 is a detail side view of part of the construction shown in Figure 1 on an enlarged scale, the view being partly broken away and partly in section;

Figure 3 is a view similar to Figure 2 showing the parts in a different position;

Figure 4 is a top or plan view, partly in section, of the construction shown in Figure 2, the view being taken in the direction of arrow 4 of that figure;

Figure 5 is a side view, partly in section, of a portion of the construction shown in Figure 1 looking in the direction of arrow 5 of that figure;

Figure 6 is a sectional view of the improved spring drum arrangement for applying the additional tension to the straps or belts, the section being taken looking in the direction of arrow 6 of Figure 4, and

Figure 7 is a detail section view of an adjustable weight which may be employed to counter weight the controller drop roll, the view being taken in the direction of arrow 7 of Figure 4.

Referring now to these drawings, the various parts of the mechanism are mounted on suitable side frames, one of which is indicated at 1.

The particular mechanism selected to illustrate the invention includes means for supporting a running roll R and a spare roll indicated at S, these rolls being mounted so that they can be moved from loading to running position. It will be understood, of course, that a single web roll may be used or any suitable mechanism may be employed for supporting the running roll and one or more spare rolls. As shown, the rolls are supported in suitable chucks or bearings 2, 3 formed in the ends of arms 4, one of which is shown in Figure 1, mounted on a shaft 5 which can be driven in any suitable manner to move the rolls from loading to running position.

As in the copending application referred to, a tension mechanism is employed which frictionally engages the surface of the web roll over which the web is being led to the press, which exerts a normal running tension on the web roll to insure sufficient or suitable tension for good printing. While the specific construction of these tension

devices may be varied, as shown, such tension devices are in the form of a plurality of belts or straps, two such straps 6, 7 being shown and arranged to have a substantial wrap or lap around 5 the unwinding roll, as shown in Figure 1, the straps following the roll as it decreases in size so that the requisite tension is kept thereon. These straps, at their lower ends, are supported, by means of hooks 8, around a bar or rod 9 10 mounted in blocks 19 suitably supported on the floor of the press-room or other suitable support.

Machines constructed in accordance with the invention will provide a normal or running tension on the belts or straps and an increased tension or pull on the straps in case of a slack or loose condition in the web, and a simple mechanism for accomplishing this has been provided by the present invention. While but two tension belts or straps are illustrated, it will be understood that in the best constructions four such straps will be provided. The mechanism shown in Figure 4 being one-half of the machine and the other half being a duplicate of that shown in Figure 4, it therefore need not be illustrated. 20 With this arrangement, when a full width roll is being used, four belts or straps would be operating, a three-quarter roll would be operating with three straps, and a half roll with two straps.

With the particular construction, illustrated 30 there is provided a mechanism for exerting a comparatively light or normal running tension on the straps and means for providing an increased tension or pull on the straps, two of these mechanisms being shown in Figure 4, marked 35 generally 11, 12, which will be more fully described hereinafter.

While the particular mechanism for controlling the pull or tension on the straps may be somewhat varied, in that selected to illustrate the 40 invention a controller mechanism is shown which includes a member which rests on a loop of the web, the tensioning mechanism being operated by an upward or downward movement of this controller member. This member is shown as a 45 roll 13 journaled in the ends of a pair of arms 14, one of which is shown in Figure 4, it being understood that this is duplicated on the other side of the machine. These arms, at their other ends, are fast on a rock shaft 15 suitably supported in bracket arms 16 secured to the side 50 frames before referred to.

The web marked W is led from the running roll under a guide roll 17 over a tension roll 18, of usual construction, under the controller 55 roll 13 to the press. The controller roll is held in the upper position, as shown in Figure 1, by the pull of the web going to the press, but if a slack occurs in the web, for any reason, this controller roll moves downwardly, and this downward movement of the controller or drop roll puts into 60 operation the mechanisms 12, whereby the increased tension required is put on the center straps, as the straps 7. It will be understood that the normal tension of the straps keeps such 65 a tension on the web that the drop roll is held in its upper position by the web tension, but the roll is permitted to drop if there is a break in the web or a slack condition from other causes.

This particular mechanism which is employed 70 for operating the means for applying increased tension to the center straps may be somewhat varied, but, as shown, this mechanism includes a controller arm 19 on the rock-shaft 15, which has pivoted thereto one end of a link 20, and at 75 its other end this link is pivoted to one end of

a pawl arm 21 secured to what may be termed a drum-shaft 22 suitably supported in bearings 22' on the bracket arm 16, before referred to. The link 20 carries a stop 23 which engages the tail 24 of a pawl 25 pivoted at 26 on the pawl arm 21, before referred to, this pawl being arranged to engage the teeth of a ratchet 27 on the drum-shaft 22, before referred to.

This drum-shaft 22 supports drums 28, one of which is shown, which together with certain parts hereinafter referred to provide the normal running tension on the belts or straps, this tension being provided by a spring 29, the end of the belt, as the belt 6, being secured to this drum.

In accordance with the invention, an improved mechanism is provided for exerting an increased pull on certain of the straps, as, for instance, the two center straps 7, one of which and its associated mechanism being shown in Figure 4, generally marked 12. This mechanism includes a double spring drum construction and includes a sleeve 30 secured to the shaft 22 and a spiral or clock spring 31, the inner end of which is secured to the sleeve and the outer end to a spring support or drum 32. This drum 32 is formed with a sleeve 33, to which the inner end of a spiral or clock spring 34 is secured, the outer end of this clock spring being fastened in the wall of a drum 35, as indicated at 36 and best shown in Figure 6. This drum 35 is provided with a hub 37 and turns freely on the sleeve 33.

The clock spring 34 is a relatively strong spring and, during the operation of the mechanism, is released to the limit permitted by the capacity of the interior of the drum 35. The spring 31 110 and the spring 29 are relatively weak, the spring 29 providing the normal running tension to the to the belt 6, and the spring 31, to which the belt 7 is secured, acting to rotate the drum 32 and keep the straps 7 in contact with the web 115 roll, ready for quick application of the heavy spring 34.

When, however, the drop roll 13 descends, through the connections heretofore described, the stop 23 is released from the pawl 25 and the pawl 120 engages the teeth of the ratchet 27, and this movement acts to turn the shaft and with it the drum 32. This movement, through the connection between the two drums, puts the tension 125 on the comparatively heavy spring 34, thereby increasing the pull on the tension strap, for as the drum 32 is turned, through the action of the pawl, the spring 34 is put under a tension which is communicated to the drum 35. It will thus be 130 understood that under ordinary starting and running conditions a web roll is held under a running tension caused by the springs 31 and 29. Under certain conditions, however, such as a break in the web or other slack condition, the 135 tension or pull on the straps is increased through the relatively heavy spring 34.

In the best constructions, means are provided for adjusting the effective weight of the drop roll 13 and, as illustrated, these means consist of a weight 38, which is slidable on a bar 39 supported in a bracket 40 secured to the rock-shaft 15, before referred to. The position of this weight or arm 39 can be adjusted to counterweight the roll 13, and it will be understood that the tension exerted by the spring mechanism described and the counterweighting of the drop roll is so proportioned that, after the pawl and ratchet mechanism and the spring 34 have acted to put the increased tension or pull on the straps, an overtravel of the roll is permitted, so as to

take up any excess web which may have run from the roll, the spring connections permitting the drop roll to extend through a considerable travel, consequently allowing a longer period of time 5 in which to stop the web roll.

In the best constructions, means will be provided for quickly tensioning the relatively heavy spring 34, so that the additional tension or pull will be applied to the straps very quickly and 10 will require but a small descent of the drop roll from the position shown in Figure 1 toward that shown in Figure 3. In the particular construction illustrated, there is provided a supplementary spring, marked 41, best shown in Figure 6, which 15 is located inside the spring 34 and secured to the sleeve 33, before referred to, the two springs being held in position, as shown in Figure 6, by set screws 42. With this construction, the initial tension of the spring 34 is provided very quickly, 20 so that the drop roll 13 only has to travel approximately one quarter of its way down to exert the required heavy tension on the straps, the balance of its travel being available to take care 25 of excess web that may be caused by the tendency of the web roll to run ahead.

It will be understood, as before stated, that the tension of the web acts to keep the drop roll 13 in its upper position, or that shown in Figure 1. To limit this movement, there is preferably 30 provided a resilient stop device, shown in Figure 5 as comprising flat springs 43 and a stop 44, and the lower travel of the roll is or may be defined by a stop pin 45, see Figure 4, with which the roll arm 14 engages and stops the downward 35 movement of the roll.

It will further be observed that the roll support which supports the main roll and the spare roll can be rotated at any desired time. When the drop roll 13 is in the upper position shown in 40 Figure 1, the pawl 25 is disengaged and the drums 32, 35 are free to rotate, so that the straps may be paid out or wound up as required but held only against the tension of the light springs 29, 45 31. If, however, the drop roll is in its down position, as shown, for instance in Figure 3, and the pawl is still in engagement with the ratchet 27, the support may still be rotated even against the action of the relatively heavy spring 34. However, if the press be started when such heavy 50 tension is on, the pull or tension on the web will at once raise the roll 13 and remove the tension from the heavy spring 34.

It will be seen with the construction shown and described that a very simple and efficient mechanism has been provided for applying a normal 55 running tension on the roll controlling straps, for providing the increased tension needed in case of a break in the web or other slack condition, and permitting overtravel of the drop roll to take up any excess slack of the web due to 60 overrun, such mechanism operating automatically and requiring practically no adjustment.

While the invention has been shown and described in its preferred form, it will be understood 65 that certain changes and variations may be made in the specific structure provided for carrying out the invention without, however, departing from the spirit of the invention as defined in the appended claims.

70 What is claimed is:

1. Web tensioning mechanism including in 75 combination friction straps engaging the surface of the unwinding web roll, spring means connected with the straps for exerting a normal running tension on the straps, a movable con-

troller roll engaging the web, spring means for exerting an increased pull on a strap to increase the tension on the roll, and connections actuated by the movement of the controller roll for actuating the latter spring means. 80

2. Web tensioning mechanism including in combination friction straps engaging the surface of an unwinding web roll, spring means connected with the straps for exerting a normal running tension on the straps, a drop roll engaging the web, spring means for exerting an increased pull on a strap, and connections actuated by the downward movement of the drop roll for actuating the latter spring means. 85

3. Web tensioning mechanism including in combination friction straps engaging the surface of an unwinding web roll, means connected with the straps and exerting a normal running tension on the straps, a drop roll engaging the web, spring means for exerting an increased pull on a strap, and connections actuated by the downward movement of the drop roll for actuating the spring means. 90

4. Web tensioning mechanism including in combination friction straps engaging the surface of an unwinding web roll, means connected with the straps and exerting a normal running tension thereon, a drop roll engaging the web, a shaft rocked by the downward movement of the roll, a spring on the shaft and connected to one of the straps, and connections operated by the movement of the shaft for tensioning the spring. 100

5. Web tensioning mechanism including in combination friction straps engaging the surface of an unwinding web roll, a spring having connection with one of the straps, a spring having connection with another of said straps, a heavier spring connected to said latter strap, and means for actuating the heavy spring to put a tension on the latter strap greater than the tension 110 exerted by the light spring. 115

6. Web tensioning mechanism including in combination friction straps engaging the surface of an unwinding web roll, a spring having connection with one of the straps, a spring having connection with another of said straps, a heavier spring connected to the latter of said straps, a booster spring connected with the heavy spring, and means for actuating the heavy spring to put a tension on the strap connected thereto greater 120 than the tension exerted by the lighter spring. 125

7. Tensioning mechanism for unwinding web rolls, including in combination straps engaging the roll surface, a comparatively light spring connected with one of the straps, a spring mechanism connected with another of the straps and comprising a light spring normally active and a heavier spring normally having minimum tension, and means for increasing tension on the heavy spring to put a tension on the strap greater than the tension exerted by the light 130 spring. 135

8. Tensioning mechanism for unwinding web rolls, including in combination straps engaging the roll surface, a comparatively light spring connected with one of the straps, a spring mechanism connected with another of the straps and comprising a light spring normally active and a heavier spring normally having minimum tension, means for increasing tension on the heavy spring, and a booster spring connected with the heavy spring for accelerating the tensioning thereof. 140

9. Tensioning mechanism for unwinding web rolls, including in combination straps engaging 145

- the roll surface, a shaft, a spring drum on the shaft to which one of the straps is connected, a double spring drum mechanism on the shaft including light and heavy springs, the heavy spring normally having minimum tension and being connected to another strap, a drop roll engaging the web, and pawl and ratchet connections actuated by the downward movement of the drop roll for turning the drum of the heavy spring to increase tension on it. 5
10. Web tensioning mechanism including in combination, a friction strap engaging the surface of an unwinding web roll, a spring means connected with the strap for exerting a normal running pull thereon, a movable controller roll engaging the web, a second spring means connected with the strap for exerting an increased pull, and a connection whereby the second spring means is tensioned by movement of the controller roll; the initial movement of the controller roll acting to exert an increased pull on the strap and further movement of the controller roll being permitted, to maintain tension on the web. 15
11. Tensioning mechanism for unwinding web rolls including in combination, a shaft, a collar secured to the shaft, a first drum rotatable on the shaft, a first spring connecting the collar to the drum, a second drum, a second spring connecting the first drum to the second drum, a strap connected to the second drum and adapted to press against the surface of the web roll, and means for increasing tension on one of the springs to increase the pressure of the strap. 20
12. Tensioning mechanism for unwinding web rolls including in combination, a shaft, a collar secured to the shaft, a first drum rotatable on the shaft, a first spring connecting the collar to the drum, a second drum, a second spring connecting the first drum to the second drum, a strap connected to the second drum and adapted to press against the surface of the web roll, a drop roll engaging the web, and connections from the drop roll for increasing tension on the second spring to increase the pressure on the strap. 25
13. In a mechanism for maintaining tension on a web drawn from a web roll, a drop roll held in movable roll supports and engaging the web, a strap held under tension and arranged to press against the roll, a spring support, a first spring connecting the strap to the spring support, a second spring connecting the spring support to an anchorage, and means connected to the movable roll supports to move the spring support when the web slackens and thereby increases the tension on the strap. 30
14. In a mechanism for maintaining tension on a web drawn from a web roll, a drop roll in running engagement with the web, a strap held under tension and arranged to press against the roll, a spring support, a heavier spring connecting the strap to the spring support, a lighter spring connecting the spring support to a fixed member, and means operable by a motion of the drop roll transversely to its axis, whereby the spring support is moved to increase tension on the heavier spring and the rotation of the web roll is checked when the web slackens. 35
15. In a mechanism for maintaining tension on a web drawn from a web roll, a drop roll in running engagement with the web and supported to move transversely to its axis when the web slackens, a shaft, a spring support rotatable on the shaft, a drum rotatable on the shaft, a spring connection between the shaft and the spring support, a spring connection between the spring support and the drum, a strap bearing against the roll and having one end secured to the drum and the other end secured to a fixed member, and means operable by motion of the drop roll transversely to its axis whereby the drum is rotated to tighten the strap when the web slackens. 40
